UNITED STATES PATENT OFFICE.

RICHARD DUANE GREEN, OF TRENTON, NEW JERSEY, ASSIGNOR TO JOHN A. ROEBLING'S SONS COMPANY, A CORPORATION OF NEW JERSEY.

WIRE ROPE.

1,405,835.

Specification of Letters Patent. Patented Feb. 7, 1922.

Application filed August 26, 1919. Serial No. 319,924.

To all whom it may concern:

Be it known that I, RICHARD DUANE GREEN, a citizen of the United States, residing at Trenton, county of Mercer, and State 5 of New Jersey, have invented certain new and useful Improvements in Wire Rope, fully described and represented in the following specification and the accompanying drawings, forming a part of the same.

10 This invention relates to heavy duty wire ropes.

Wire ropes for general hoisting purposes, where sheave work requires considerable flexibility, are generally formed with a fibre 15 core of manila or other suitable fibre and the wire strands which, of course, take the strains imposed on the rope during use are laid up helically on this core.

With particularly heavy duties such as are 20 encountered in present-day commercial use, the excessive tension, by a concentration of pressure by the wire strain-bearing strands on the core, eventually causes its disintegration. When the core thus ceases to function, 25 the wire strands are supported only by each other and the result is a tendency of the strand wires to nick. This nicking not only shortens the life of the rope, but in addition it tends to lock the strands, thus restricting 30 strand and wire movement when the rope is used in sheaves, causing the wires to break.

It is the object of the present invention to provide a heavy duty wire rope which includes in its construction a strand support 35 lying between the wire strands, which take the strains imposed on the rope during use, and the core, said support being of such character that it prevents the disintegration of the core and the resulting shifting of the 40 strands from their original position as they are laid in the rope, whereby nicking and wear of the strands on each other is prevented, and a rope is produced which has a higher efficiency and a longer life.

45 With this general object in view, the invention consists in the combinations, details of construction and arrangements of parts which will first be described in connection with the accompanying drawing and then 50 more particularly pointed out in the claims.

In the drawing,—

Figure 1 is a plan view, with parts broken away and removed, of a heavy-duty wire rope constructed in accordance with the invention;

Figure 2 is a similar view showing part of the rope in the process of construction; and

Figure 3 is a cross-sectional view taken transversely through the completed rope.

Referring to the drawings, a rope is illustrated which, as shown, is provided with a fibre core 4 comprising a number of strands laid up spirally in the usual manner. This core may be constructed of any suitable fibre, such as manila. Laid up on the core 65 are a plurality of wire strands 6 which take the strains imposed on the rope during service. Each strand preferably consists of a plurality of small individual wires which may be of high carbon steel, these wires being spirally laid on each other in the usual manner. Although six strands of nineteen wires each are shown, it will be understood that any other suitable arrangement may be used.

70 Ropes constructed in accordance with the invention will embody a support for the strain-carrying wire strands located between the core and the strands, the function of this strand support being to prevent, as far as possible, the strands from shifting, during the use of the rope, from their original position to a position where they are supported solely by each other. Where the strain-carrying strands are wound directly 80 on the fibre core, even though the strands are so disposed in the first instance that they are supported substantially out of wearing contact with each other, the heavy strains which these strands carry disintegrate the 85 core. This permits a reduction in diameter of the rope and a consequent stretching. This brings the strands into such position that they are supported by each other, so that, in subsequent use, wear and nicking 90 result. In what are regarded as the best constructions, this strand support will be so laid up on the core as to place the core under an initial compression so that the core with the support will be substantially 95 100 incompressible, though, as hereinafter pointed out, the strand support may be deformable. While the construction of this strand support may be varied, in the construction illustrated, the strand support comprises a narrow flat steel band or flat wire

5. This band or flat wire is spirally laid up on the fibre core under considerable tension, so that the core is placed under an initial compression. The band 5 is preferably 105 110

so spiralled that the edges of adjacent convolutions are substantially contiguous, so as to avoid bearing points for the outer strands between the convolutions and to hold the lubrication in the core. These edges are shown as square, but may be rounded if desired, and this may be found preferable, especially in large ropes, as avoiding all possibility of the edges cutting the core. A 10 half round or similar form of band may be used, with the rounded side next the core, which will taper off the pressure on the core and reduce liability to injuring the core in bending over sheaves. For convenience in manufacture, the protecting band 5 may be made of several alternating pieces, two being shown in Fig. 2.

With the construction described, the pressure of the wire strands is taken by the 20 strand support and the heavy pressure of the strands directly on the core centre is avoided. Further, when the strand support is so laid on the core as to place it under initial compression, the corrugations of the fibre 25 strands are, to a certain extent, flattened out, thus presenting a more cylindrical surface to the protector and strand support. As a result, concentration of pressure on the fibre strands is prevented, the fibre core has a 30 much higher compressive resistance and supports the strands so as to prevent wear on each other and consequent nicking, and the life of the rope is thus prolonged. The rope is more flexible and has a higher efficiency, that is, a higher percentage of the 35 total strength of its component wires, than the usual fibre centre ropes.

The invention further includes the provision of a strand support that substantially 40 conforms to the configurations of the wire strands and is of a softer metal than the wires. This may be accomplished, for example, by a support sufficiently incompressible when wound on the core to withstand 45 the pressure of the wire strands, but somewhat deformable thereunder. In the present exemplification, the supporting band 5 is made of comparatively soft annealed steel. When the wire strands 6 are laid up on the 50 covered core, the tension exerted tends to deform the metal of the support 5 into the configurations of the strands. This tendency is increased when the completed rope is placed under high working tension. As a result, the 55 metal finds its way into the interstices of the wire strands and provides a relatively soft separator for the high carbon steel wires, and thus prevents nicking of the wires.

The thickness of the metal band for this purpose is important, as it must be thick 60 enough to prevent concentration of pressure of the wire strands on the fibre centre, and must not be so heavy that it will not flow under the tension of manufacture and use, so as to fill up the interstices and give the 65 required protection between the strands.

While the invention has been described in connection with the usual fibre or rope strand cores, and is especially valuable in such use, it will be understood that the invention, considered broadly, is applicable also with other compressible cores, as defined by the claims.

What I claim is:

1. A wire rope comprising a fibre core, a 75 strand support so laid up on the core as to place the same under an initial compression such as to prevent substantial compression of the combined core and support, and a plurality of strain-bearing wire strands laid up 80 spirally on the strand support.

2. A wire rope comprising a fibre core, a strand-supporting metallic band spirally laid up on the core to place the same under an initial compression, and a plurality of 85 wire strands laid up spirally directly on the band.

3. A wire rope comprising a compressible core, a strand support of substantially softer metal than the wires of the strands laid up 90 spirally on the core, and a plurality of wire strands laid up spirally on the support.

4. A wire rope comprising a compressible core, a plurality of wire strands and a metal strand support located between the strands 95 and the core and in contact with the strands, the strand support being deformable under the tension of the wire strands so that a part of its surface enters the interstices between the strands.

5. A wire rope comprising a fibre core, a tenacious and deformable metal band laid up spirally on the fibre core to place the same under an initial compression and form a strand supporting core protector, and a plurality of wire strands laid up spirally on the 105 deformable metal band.

6. A wire rope comprising a fibre core, a band of thin tenacious metal laid up spirally on the fibre core to substantially cover the same and form a support for the strands, 110 and a plurality of wire strands laid up spirally on the protected core.

In testimony whereof, I have hereunto set my hand.

RICHARD DUANE GREEN.
